CIGAR LIGHTER

Filed Aug. 18, 1928

UNITED STATES PATENT OFFICE

CHARLES RUBSAMEN, OF RICHMOND HILL, NEW YORK, ASSIGNOR TO WILLIAM DEMUTH & COMPANY, A CORPORATION OF NEW YORK

CIGAR LIGHTER

Application filed August 18, 1928. Serial No. 300,533.

This invention relates to cigar lighters, an object of the invention being to provide a simple and efficient means for throwing sparks from a block of pyrophoric alloy, commonly known in the trade as flint, to ignite the wick.

A further object is to provide an improved construction and arrangement of spark controlling arm or lever and an improved 10 mounting therefor which automatically or mechanically completes the throw of the arm to operate the device after the movement of the arm is manually initiated.

A further object is to provide a device of 15 this character which will be simple in construction, relatively cheap to manufacture, easily assembled, adjusted and repaired and one which will not be apt to get out of order after continued use.

20 With these and other objects in view, the invention consists in certain novel features of construction and combinations and arrangements of parts, which will be more fully hereinafter described and pointed out in the 25 claims.

In the accompanying drawings—

Figure 1 is a view, mainly in side elevation but partly broken away and in section, illustrating my improved lighter;

30 Figure 2 is a view in transverse section on the line 2—2 of Figure 1;

Figure 3 is a view, partly in elevation but mainly in section, of the upper portion of the device;

35 Figure 4 is a view similar to Figure 3 but showing the arm or lever in its upward position with the wick ignited;

Figure 5 is a sectional plan view on the line 5—5 of Figure 2;

40 Figure 6 is a fragmentary view in transverse section on the line 6—6 of Figure 3;

Figure 7 is a fragmentary view, partly in elevation and partly in section, showing the flint or alloy follower and its manner of connection with the spring;

Figure 8 is a top plan view of the spark throwing arm or lever;

45 Figure 9 is a perspective view of the bifurcated sleeve 15;

Figure 10 is a perspective view of the spring housing 17.

1 represents a casing adapted to contain absorbent or other material 2 saturated with a suitable liquid which is supplied through 55 an opening 3 in the bottom of the casing. This opening is normally closed by a screw plug 4. A wick tube 5 is secured in the top plate 6 of the casing 1 and supports a wick 7 which extends down into the casing and remains saturated with liquid for burning.

A tubular barrel 8 extends longitudinally of the casing 1 and is fixed in the bottom of the casing at its lower end, and its upper end is located centrally in an opening 9 in 60 the top plate 6, said opening 9 being appreciably of greater diameter than the upper end of the barrel.

The barrel 8 at its upper end functions as a guide for a block of alloy 10, commonly known as flint, and this block 10 is forced upwardly and outwardly through the medium of a follower 11 back of or below the same.

The follower 11 is made with a headed 75 pin 12, which may be located between any of the convolutions of a coiled spring 13, the lower end of said coiled spring being fixed to a screw plug 14 screwed into the lower end of the barrel 8.

80 It will thus be noted that the follower 11, spring 13 and plug 14 constitute in effect a single member which can be removed and replaced at will, and by reason of the engagement of the headed pin 12 between the convolutions of the spring 13, the follower and the spring are held together and a certain amount of adjustment is permitted as the head may be located between any of a series of convolutions by simply turning the 85 follower when in proper engagement with the spring.

A forked sleeve 15 fits loosely on the barrel 8 and its upper forked or bifurcated end is freely movable through the opening 9 in the top 6 of casing 1. A coiled spring 16 is located around the barrel 8 below the sleeve 15 and has an abutment against the lower end of the spring housing so that this spring has an outward pressure on the sleeve 15 for a pur- 95 100

pose which will more fully hereinafter appear.

I illustrate the sleeve 15 in perspective in Figure 9, in which it will be noted that this sleeve at its upper bifurcated portion has forwardly extending fingers 19 presenting extending bearing surfaces at the upper end of the sleeve, and the rear or back portion of the sleeve is recessed or cut away as shown at 20.

The spring housing 17 above referred to is of tubular form, appreciably larger than the barrel 8, and encloses the upper portion of the barrel and acts as a housing for the spring 16. This housing is perforated at its lower end to receive the barrel and has a tight juncture with the barrel to prevent leakage, and the flanged upper end of the housing is rigidly fixed and countersunk in the top or end 6 of the casing 1. A pair of upstanding perforated lugs 21 are made integral with the upper end of the housing 17. These lugs 21 support a pin 22 on which my improved arm or lever 23 is pivotally mounted. This arm or lever 23 is made with perforated ears 24, 24 receiving the pivot pin 22 and carrying on their inner faces inwardly projecting studs 25 which bear against the upper faces of the furcations of the bifurcated sleeve 15.

A toothed sparking wheel 26 is also mounted on the pivot pin 22, and as a matter of fact this wheel 26 constitutes a segment, the flat side of which engages the under face of the arm 23 so as to compel the wheel 26 to turn with the arm, and the teeth of this wheel 26 are in engagement with the sparking block 10.

The arm or lever 23 carries a snuffer 27 adapted to engage over the tube 5 and extinguish the light from the wick 7, as is common in the art.

In connection with my improved lighter I may employ a windshield 28 which is of general U-shape in plan and which has a recessed baseplate 29 resting on the top 6 and removably secured in place by a headed screw 30 screwed into the top 6 and positioned in a slot 31 in the baseplate 29 so as to clamp the windshield securely in position.

This windshield may have any number of openings 32 adjacent its lower portion to allow for a sufficient draft of air, and the lever or arm 23 is of such shape as to function as a cover for this windshield when the arm 55 is in horizontal position.

The arm 23 at its forward or free end has a small lip 33 under which the finger may be positioned to lift the free end of the lever, and the opposite end of the lever is flared or curved outwardly or upwardly, as shown at 34, forming a finger receiving tongue which may be depressed to initially move the arm.

The recessed portion of the sleeve 15 is 65 such as to accommodate the flared or curved

portion of the arm and allow the same to remain in its upper or operative position, as clearly indicated in Figure 4 of the drawings.

The operation is as follows:

Figures 1, 2, 3, 5 and 6 show the lighter in 70 inoperative position, that is, with the lever or arm 23 in its downward position, and when in this position it will be noted that the studs 25 are in the rear of the vertical plane of pivot pin 22; in other words, they are past 75 dead center with relation to the pin 22 so that the upward pressure of the spring 16 on sleeve 15 tends to hold the arm or lever 23 in this position. To ignite the wick 7 the arm or lever 23 is initially moved either by 80 an upward pressure on the small lip 33 at the free end of the lever and by a downward pressure on the tongue 34 at the rear end of the arm or lever. Either of these movements must be sufficient to swing the arm 23 to a 85 position far enough to advance the studs 25 forwardly or to the left of Figure 1 sufficiently far to pass dead center with relation to pivot pin 22, and when such a position is reached the upward movement of the spring 90 16 on the sleeve 15 will complete the movement, giving a rapid throw to the arm from its horizontal to its vertical or upright position, and during this movement the toothed wheel 26 will throw sparks from the block 10 95 to ignite the wick. When the arm is swung downward into horizontal position it will of course extinguish the flame and cover the windshield, as above explained.

The spring-pressed sleeve 15, therefore, 100 functions to hold the arm or lever 23 in either of its extreme positions and functions to rapidly throw the arm upwardly after its movement is manually initiated.

While I have illustrated what I believe to 105 be a preferred embodiment of my invention, it is obvious various changes and alterations might be made in the general form of the parts described without departing from my invention and hence I do not limit myself to 110 the precise details set forth but consider myself at liberty to make such changes and alterations as fairly fall within the spirit and scope of the appended claims.

I claim:

1. A lighter including a casing, a wick mounted on the casing, a spring housing extending into the casing, an arm having one end pivotally mounted on the casing adjacent the housing, a sparking means carried by the arm, a sleeve in the housing and having its outer end bifurcated, studs on the arm and spaced outwardly of the axis of the pivotal mounting of the arm and engaged by the bifurcated outer end of the sleeve, the bifurcated portion of the sleeve being offset from the body of the sleeve, a resilient means urging the bifurcated end of said sleeve against the studs for causing oscillation of the arm, to actuate the sparking means, 120 125 130

2. A lighter including a casing, a wick mounted on the casing, a spring housing extending into the casing, an arm having one end pivotally mounted on the casing adjacent the housing, a sparking means carried by the arm, a sleeve in the housing and having its outer end bifurcated, studs on the arm and spaced outwardly of the axis of the pivotal mounting of the arm and engaged by the bifurcated outer end of the sleeve, the bifurcated portion of the sleeve being offset from the body of the sleeve, a resilient means urging the bifurcated end of said sleeve against the studs for causing oscillation of the arm, to actuate the sparking means, the bifurcated end of the sleeve having a cut-out portion, the arm adjacent the pivot having a lip engageable with the cut out portion for limiting the movement of the arm when oscillated by the sleeve.

Signed at Richmond Hill in the county of Queens and State of New York this 15th day of August A. D. 1928.

CHARLES RUBSAMEN.
